UNITED STATES PATENT OFFICE

WILLIAM W. BATCHELDER, OF BOSTON, MASSACHUSETTS.

IMPROVEMENT IN APPARATUS FOR LIGHTING GAS BY ELECTRICITY.

Specification forming part of Letters Patent No. 94,545, dated September 7, 1869.

To all persons to whom these presents may come:

Be it known that I, WILLIAM W. BATCHELDER, of the Highlands of Boston, of the county of Suffolk and State of Massachusetts, have made a new and useful invention having reference to the Inflammation of Gas by Electricity; and I do hereby declare the same to be fully described in the following specification, and represented in the accompanying drawings, of which—

Figure 1 is a front elevation, Fig. 2 a side view, and Fig. 3 a vertical section, of my new gas-lighting apparatus.

In the form in which it is represented in the drawings the apparatus is for the purpose of lighting a cigar. Its main features, however, may be applied for illuminating or various other purposes.

In the drawings, A denotes a conic frustum, composed of vulcanized india-rubber or vulcanite, or other equivalent material capable of generating electricity by the friction of silk or cloth when rubbed on its surface. It is mounted on a metallic stand, B, and provided with a metallic bell or cap, C, lined with silk or other proper exciting material. The said bell or cap C is connected with the hollow stem D of a gas-cock, X, by means of an insulator or column of vulcanite, E. The stem D turns freely within a metallic knob, F, mounted on the top of the insulator E.

A block, G, provided with two prongs, a a, extended from it in manner as represented, turns freely on the stem, and with the stem constitutes a gas-cock.

From one side of the block a gas-burner, H, extends, and from the opposite side of the block a lever or weighted arm, I, is projected.

Fig. 4 is a longitudinal section of the lever, the block, and the gas-burner, the section exhibiting a hole, b, made laterally out of the tubular stem D.

A conduit or tube, K, projects from and opens into the stem between the two prongs a a. It is intended that a flexible or india-rubber tube or hose for the conveyance of gas into the stop-cock shall be applied to and so as to open into the conduit K.

To one side of the burner a wire or metallic arm, M, terminating at its upper end in a

knob, c, is affixed, an insulator, N, of vulcanite, being fixed to the opposite side of the burner.

Another such wire or arm, O, is extended through the insulator, and terminates at its upper end in a knob, d, the two knobs being arranged at a short distance apart, and so that a stream of gas, on making its exit from the burner, may pass between them.

A metallic chain, e, extends from the lower end of the wire O to the top of the metallic bell C.

The arm or lever I has a heavy handle or weight, e', fastened on it. By taking hold of this handle and raising it, so as not only to turn the block or movable part of the stop-cock on its stem, but to lift the bell or hollow cone off the vulcanite frustum, communication with the burner will be opened, so as to supply it with gas, provided gas be in the conduit. At the same time a current of electricity will be generated, and a spark will pass from one of the knobs to the other, and through the current of gas flowing from the burner, and will inflame it, the knobs being arranged relatively to the burner in manner as represented.

After having lighted or set fire to his cigar, or employed the gas-flame for any other purpose, the person should restore the bell to place on the vulcanite cone or frustum, and the handle should be allowed to drop, and thereby turn the stop-cock cut-off or block G, so as to stop the flowage of gas to the burner, and thereby extinguish the flame. Thus, with this apparatus, gas will only be consumed when required for use.

I herein make no claim to the combination of a generator of electricity and an electric circuit with a gas-burner; nor do I herein claim the subject of the Patent No. 26,964, granted to me on January 21, 1860; nor do I claim the application of the weighted lever to the burner and gas-cock provided with a flexible supply-tube.

What I do claim as my invention is as follows, viz:

1. The combination of the friction electrical generator, current devices M O, and insulators E N, substantially as described, with the

lever I, the gas-burner H, gas-cock X, and conduit K, as set forth.

2. Also, the combination of a flexible gas conduit or hose, L, with the gas-burner H, gas-cock, friction electrical machine or generator, and broken circuit, as explained.

3. Also, the combination of the gas-cock, gas-burner H, and conduit L, and broken elec-

trical circuit with the electrical exciter or bell C, so as to be movable with it from and to the vulcanite frustum A, or its equivalent, when the latter is stationary in position.

WILLIAM W. BATCHELDER.
